US00D592529S

(12) **United States Design Patent**
Friebe et al.

(10) **Patent No.:** **US D592,529 S**
(45) **Date of Patent:** **** May 19, 2009**

(54) **FOIL PACKAGE**

D248,373 S 7/1978 Allen

(75) Inventors: **Joachim Friebe**, Heimertingen (DE);
Andreas Michalsky, Memmingen (DE);
Maurice Habram, Kempten (DE);
Agata Surdziel, Kempten (DE); **Peter Ganz**, Untrasried (DE)

(Continued)

(73) Assignee: **Huhtamaki Ronsberg**,
Zweigniederlassung der Huhtamaki
Deutschland GmbH & Co. KG (DE)

FOREIGN PATENT DOCUMENTS

(21) Appl. No.: **29/299,502**

Primary Examiner—Caron Veynar

Assistant Examiner—Abraham Bahta

(22) Filed: **Dec. 27, 2007**

(74) Attorney, Agent, or Firm—Knobbe Martens Olson & Bear LLP

Related U.S. Application Data

(62) Division of application No. 29/231,547, filed on Jun. 7, 2005, now Pat. No. Des. 582,790.

(30) **Foreign Application Priority Data**

Apr. 19, 2005 (EP) 000330485

CLAIM

(51) **LOC (9) Cl.** **09-02**

The ornamental design for a foil package, as shown and described.

(52) **U.S. Cl.** **D9/772**

(58) **Field of Classification Search** D9/702–703,
D9/503, 414, 500, 516, 505, 428, 529, 519,
D9/564, 454, 549–550, 504, 548, 686–693,
D9/434–436; 206/484; 222/92; 220/495.03,
220/260, 890; 426/106; 428/35.2; D28/76,
D28/88–89, 91, 73, 78, 82; 215/316, 317,
215/400; 132/293

See application file for complete search history.

DESCRIPTION

(56) **References Cited**

FIG. 1 is a perspective view of the foil package showing the package separately for ease of illustration without the lid;

FIG. 2 is a bottom view thereof;

FIG. 3 is a top view thereof;

FIG. 4 is a front view thereof;

FIG. 5 is a perspective view thereof with a foil package lid secured;

FIG. 6 is a perspective view thereof with the foil package lid partially removed; and,

FIG. 7 is a perspective view thereof with the foil package lid almost completely removed.

The broken line portions of the foil package are for illustrative purposes only and are not intended to limit the claimed design to the features shown in broken lines.
